UNITED STATES PATENT OFFICE.

IRA D. WALTER, OF HARRISBURG, ARKANSAS, ASSIGNOR OF THREE-EIGHTHS TO THOMAS W. JOYNER, ONE-EIGHTH TO WILLIAM D. SHELTON, AND ONE-EIGHTH TO CHARLES J. MITCHELL, ALL OF HARRISBURG, ARKANSAS.

SAFETY DEVICE FOR RAILWAY CROSSINGS.

Application filed January 17, 1924. Serial No. 626,750.

To all whom it may concern:

Be it known that I, IRA D. WALTER, a citizen of the United States, residing at Harrisburg, in the county of Poinsett and State of Arkansas, have invented a certain new and useful Improvement in Safety Devices for Railway Crossings, of which the following is a full, clear, and exact description.

10 Various devices are used for the purpose of guarding the intersections of roadways with railways to prevent collisions between road vehicles and trains, and for warning persons upon a roadway of the 15 proximity of its intersection with a railway.

These devices take various forms, including gates, visible signals, audible signals, and combinations of same, and up to the 20 time of the extensive and general use of motor vehicles, when horse-drawn vehicles comprised the bulk of traffic upon roadways, a "grade crossing" as the intersections of roadways with railways at grade 25 are commonly known, were well guarded against accidents incident to collision between trains and road vehicles by such gates and audible and visible signals. However, since the motor vehicle has come so generally into use, and since the bulk of road traffic 30 is now composed of motor vehicles, and as the speed which may be attained by such vehicles renders it impossible to stop suddenly when traveling at high speed and 35 without sufficient warning of the proximity of a grade crossing, it has become necessary to depart from the ordinary types of gates, audible signals and visible signals, and to resort to some sort of crossing guard 40 which will give the motorist such ample warning of the proximity of the grade crossing as to enable him even when traveling at high speed, to stop within a safe 45 distance of such crossing when a train upon the railway is approaching the crossing.

The object of my invention is to provide a safety device or guard for grade crossings, which will give the operator of a vehicle approaching such crossing ample 50 warning of its proximity, and, at the same time, of the proximity of a train to the crossing, and which will, if such warning

is disregarded by the operator, especially in the case where his vehicle is one having pneumatic tires, so injure the tires that 55 unmistakable evidence of his having failed to heed the warning will be provided.

It will therefore be seen that, in order to attain the highest possible degree of efficiency, I have recognized three indispensable essentials in dealing with the motorist. These are, first, to warn him by suitable signals when within a potential danger zone; second, to successively designate the progressive approach of a train when within a certain distance of the highway or crossing; and, third, to obstruct the crossing, so far as automobile traffic is concerned, when the train has reached a point where an attempt to pass in front of the 70 engine would be extremely hazardous.

Aside from loss of life, bodily injury, and complete or substantial wrecking of his vehicle, the damage to such vehicle which is most exasperating to a motorist is the 75 blowing out or puncturing of his tires, and inasmuch as with my device I provide for the practically certain mutilation of all of the tires of the vehicle, education of the driving public to the end that they may 80 know what property loss, regardless of bodily injury, they may sustain by disregard of the warning given by the device of my invention, should result in a reasonable regard for such warning.

To this end, the invention consists in a safety device for railway crossings, that is, intersections at grade between railways and roadways, comprising essentially a plurality, preferably three, of visible signal devices located in or adjacent to the roadway, at varying distances from the railway on both approaches of the roadway thereto, said signal devices being interconnected for simultaneous operation, and connected with 90 means spaced at suitable intervals adjacent to the railway tracks and adapted for successive operation upon the passage of a train to actuate the signal devices, and a barrier located adjacent to the railway 95 tracks and including a plurality of tire mutilating spikes adapted to be projected above the plane of the surface of the roadway simultaneously with the actuation by

the train of the last track adjacent means above mentioned, and a track adjacent device adapted to be actuated by the train after it has crossed the roadway for the 5 purpose of retracting said spikes and of resetting said signal devices; and in various details of construction, as I will proceed now to explain and finally claim.

In the accompanying drawings illustrating the invention, in the several figures of which like parts are similarly designated, Figure 1 is a diagrammatic view showing the general arrangement of the various parts of my device installed at a grade crossing. Fig. 10 shows, upon a larger scale, the various devices located adjacent to the railroad tracks whereby the visible signal devices and the barrier may be actuated during the passage of a train. In this figure all of these 15 devices are shown arranged in connection with a single track railroad, but they may be equally well applied to a road having any number of tracks, their respective arrangement being the same. Fig. 3 is a plan view 20 on a still larger scale of one of the track adjacent devices and its connected mechanism, and showing the device in normal and actuated positions. Fig. 4 is a side elevation 25 of the parts shown in Fig. 3. Fig. 5 is a section taken on line 5—5 of Fig. 3 and showing the means for supporting the swinging end of the cam member of the track adjacent device. Fig. 6 is a side elevation showing, in broken lines, the pilot of a locomotive, and in full lines the roller mechanism carried thereby for engagement with the cam members of the track adjacent devices. Fig. 7 is a sectional plan view of the 30 supporting base of one of the visible signal devices, showing the operating mechanism therefor. Fig. 8 is a sectional elevation taken on the line 8—8 of Fig. 7. Fig. 9 is a plan view of the signal head. Fig. 10 is a fragmentary plan view of the barrier, portions being broken away to reveal certain 35 parts of the mechanism thereof. Fig. 11 is a fragmentary sectional elevation of the parts shown in Fig. 10. Fig. 12 is a section taken on the line 12—12 of Fig. 11. Fig. 13 is a section taken on the line 13—13 of Fig. 11. Fig. 14 is a fragmentary sectional view showing 40 the spiked bar in elevated position.

Referring now particularly to Fig. 1, the invention, as hereinabove explained, comprises a plurality, preferably three, of visible signal devices A₁, A₂, and A₃, same being duplicated upon each approach to the railway B, the signals A₁ being located at a distance of approximately 300 feet from the railway, the signals A₂ being located at a distance of approximately 150 feet from the railway, and the signals A₃ being located only a short distance, say 10 or 15 feet from the railway.

65 As shown in the drawings, these signals

are arranged in approximately the center of the roadway, and it is in such position that I believe they will most successfully serve their purpose, as anyone approaching the railway cannot fail to see a signal located directly in his path. However, the signals may be located at the side of the roadway, and of course such location of them would be imperative in case the roadway were not of sufficient width to permit a 70 vehicle to pass around an obstruction located in its center.

All of the signal devices are connected for simultaneous operation by means of rods or cables 1, and these rods or cables are connected through fulcrum members 2 with suitable devices C₁, C₂ and C₃ located adjacent to the right hand rail of each track of the railway, the devices C₁ located approximately 400 feet from the roadway, the devices C₂ at approximately 300 feet from the roadway, and the devices C₃ at approximately 200 feet from the roadway on each approach thereto, and these devices are connected to each other and to the fulcrum members 2 by means of cables 4 as will be later described more in detail.

After the signal devices A₁, A₂, A₃ have been actuated to signal the approach of a train, it is necessary, after the train has 95 passed the crossing, to reset these devices to their initial position, and for this purpose I provide devices D similar to the devices C₁, C₂ and C₃ and similarly positioned adjacent to the railway tracks but across the roadway from the other devices and connected with the fulcrum members 2 by rods or cables 5. As hereinbefore indicated, I provide a barrier E which I prefer to locate just inside of the right hand rail of one of the tracks, though it may be otherwise positioned across the roadway if desired, and connect this barrier with the track adjacent devices C₃ and D in such a manner that its tire mutilating spikes will be projected when 100 device C₃ is actuated by an approaching train, and will be retracted when the device D is actuated upon the passage of the locomotive across the roadway, as will be hereinafter more fully explained.

105 Each of the signal devices A₁, A₂, A₃ is provided with a rotatable head 6 (Fig. 8) mounted upon a vertically rotatable shaft 7 supported within a stationary support or sleeve 8 carried by a supporting base 9 which 110 forms an enclosure for the working parts of the signal device and which I prefer to mount upon a concrete foundation 10 located a suitable distance below the surface 11 of the roadway so that approximately only the support 8 and the head 6 and its associated parts will stand above the roadway.

115 The rotatable head 6 is enclosed, except for one quarter of its circumference, within a shield 12, and the head, which, as will be 120

seen is cylindrical, has its circumference divided into four exhibiting spaces 13, each adapted to receive a translucent indicia-carrying plate 14.

5 One of the plates 14 is provided with the legend "R. R. danger" which will serve to indicate to a person approaching the signal devices that a railway crosses the roadway, the next plate in rotative succession will 10 bear the legend "Train 400 feet" or a similar legend, to indicate to the approaching driver that there is a train within 400 feet of the crossing; the next plate in rotative succession will bear the legend, "Train 300 15 feet", or a similar legend to indicate that the train is within 300 feet from the crossing; and the fourth or final plate in rotative succession will bear the legend "200 feet stop", or a similar legend to indicate that 20 the train is within 200 feet of the crossing and that the driver should stop his vehicle, as progress across the tracks after the showing of this signal will in all probability result in a collision.

25 I prefer to have the plates bearing the legends "R. R. danger" and "200 feet stop" colored red, the common color for a danger signal, and the other indicia-bearing plates may be of any other contrasting colors as 30 desired.

Any suitable light, such as an electric light or an oil lamp may be enclosed within the rotatable head for the purpose of illuminating the indicia-bearing plates, and, in 35 case an electric lamp is used, any well known type of switch may be provided for illuminating the signals upon actuation of the rotating means.

This successive rotation of the heads of 40 the signal devices is accomplished by means of the rods or cables 1 and their connections with the fulcrum members 2 and track adjacent devices C₁, C₂ and C₃ as hereinabove indicated, the rods 1 being suitably connected with slide rods 15 and 16 preferably forming a part of a slide member 17 mounted within the base 9 and carrying a pawl 18 arranged for engagement with a ratchet wheel 19 mounted upon the lower end of the 45 shaft 7. This slide member 17, through its connections with the rods or cables 1 will be moved to the left (Fig. 7) upon actuation of one of the track adjacent devices and will, through its pawl, rotate the ratchet wheel 19 and with it the rotatable head 6 through 50 a quarter turn, and after the track adjacent device has been passed by the locomotive of the train and has returned to normal position, the slide member 17 will be returned to the position shown in Fig. 7 by means of a 55 heavy spring 20. Reverse rotation of the ratchet wheel 19 is prevented by means of a pawl 21.

60 Referring now particularly to Figs. 10 to 14 inclusive, the barrier E hereinabove men-

tioned comprises a casing 22 forming a housing for the working parts, and adapted to be positioned upon and supported by the railroad ties, and within this housing is mounted a guide frame comprising longitudinal side members 23, 23' and end members 24 suitably secured together as by bolts 25. Within this guide frame is mounted a vertically movable bar 26 provided with a plurality of spikes 27 arranged approximately two or two and one-half inches apart throughout its length, and this bar, when in normal depressed position, rests upon the bottom of the casing 22. Journalled in downward extensions 28 of the side members 23, 23' are short shafts 29 carrying lever members 30 arranged between the side members 23, 23' and they also carry, outside of the member 23' and between it and the side wall 31 of the casing 22, segmental lever plates 32 connected through arcuate slots 33 in the side member 23' with lugs 34 carried by the lever members 30. All of the plates 32 are connected together for simultaneous operation so as to result in concerted action 35 in elevating the spiked bar 26 through the lever members 30, by means of links 35 pivoted to each other and to the plates 32 by studs 32', and the last of these bars 35 at each end of the device extends through 40 the adjacent end of the casing 22 and is connected in any suitable manner, as by means of rocker arms 36 and 37 respectively upon rock shafts 38 and 39 respectively and rocker arms 40 and 41 upon the rock shafts 38 and 39 respectively with rods or cables 42 and 43, which in turn are connected for operation with the track adjacent devices C₁ and D respectively.

45 By this arrangement, it will be seen that when the devices C₁ are actuated by a passing train, the bars or links 35 will be moved to the left, Fig. 11, and will, through the plates 32 and lugs 34, swing the lever members 30 about their pivots 29 and elevate the spiked bar 26; and when the track adjacent devices D are actuated by a train after having passed the crossing, the bars or links 35 will be moved to the right, Fig. 11, and will 50 return the parts to the positions shown in Fig. 11.

55 It may be here noted that when the spiked bar 26 is in fully elevated position, the lugs 34 will have reached the upper ends of the slots 33 and will lie directly at dead center with respect to the shaft 29, whereby all pressure which may be brought to bear against the projecting spikes 27 will, instead of tending to impart a turning movement to the lever members 30, be borne directly by the upright ends of the lever members and in direct vertical line through their pivots.

60 The weight of the spiked bar 26 is preferably such that the initial return or de-

pressing movement of the lever members 30 will cause the bar to descend of its own accord, thereby dispensing with the necessity for the use of springs for returning it to depressed position.

All of the parts contained within the casting 22 are covered and protected by means of an arcuate cover plate 44 provided with openings 45 through which the spikes 27 may be projected upon elevation of the bar 26.

In order that foreign substances may be excluded from the interior of the casing and its contained working parts, it is of course necessary to provide a means of closing or covering the openings 45. This I accomplish by means of a longitudinally extending guard plate 46 pivotally carried upon the ends of cam members 47. These cam members are pivoted at 48 upon the ends 24 of the guide frame and are provided with cam slots 49 with which engage lugs 40 formed on the ends of the bar 26 and extending through vertical slots 51 (Fig. 13) in the end plates 24. By this arrangement it will be seen that when the spiked bar 26 is elevated, the lugs 50, traveling in the cam slots 49 of the plates 47, will cause the guard plate 46 to be moved out of covering position with respect to the openings 45 and will permit the spikes 27 to be projected through these openings. Upon descent of the bar 26, reverse movement of the guard plate 46 will take place and the openings 45 will again be covered. Inasmuch as it is necessary to form a slot 52 in the cover 44 to accommodate the movement of the portion of the cam plate 47 which carries the ends of the guard plate 46, some means must be provided for preventing entrance of foreign substances through this slot 52, and to this end I provide a raised covering housing 53 which may be bolted or otherwise suitably secured to the cover 44, thereby completely enclosing the working parts.

I deem it advisable to provide an abutment or stop to limit the movement of the plate 46 in closing direction and to provide means for enabling the wheels of a vehicle to ride over this bar 46 without disturbing it, and such an abutment is preferably formed by a plurality of gradually upwardly sloping members 54 of substantial saw-tooth conformation. This saw-tooth formation is used so that the contact between the bar 46 and the abutment will be composed only of a series of upstanding sharp edges rather than a continuous edge and thereby the chance for lodgment of dirt, pebbles and the like as far as possible prevented and the effective closing operation of the plate 46 ensured.

The construction of my barrier as above described makes it possible to partially fill the casing with grease or heavy oil to there-

by afford efficient and sustained lubrication of all of the working parts.

Referring now to the track adjacent devices, which, when operated upon the passage of a train, impart movement to the signal devices and the barrier hereinbefore described, attention is directed particularly to Figs. 1 to 6 inclusive.

Each of the track adjacent devices C_1 , C_2 , C_3 and D includes a cam member 55 pivoted upon a stand 56 (Figs. 3 and 4) suitably secured upon the end of a tie, if a tie should be located in convenient position, or upon a plate 57 (Fig. 2) spanning adjacent ties. The opposite or swinging end 58 of each of the cam members is supported by an upstanding arcuate plate 59—see particularly Figs. 3, 4 and 5,—which, in addition to its function as a support, furnishes a stop, by means of a shoulder 60, as will later appear, and, by means of a slot 61, provides means for holding down the end 58 of the cam member, as hereinafter described.

The arcuate member 59 is mounted upon a plate 62 supported upon adjacent tie ends, and this plate 62 in the case of the members C_1 and C_2 forms a support for a bell crank lever 63 suitably connected by one of its arms 64 through a rod or cable 4 and flexible connection or chain 66 with a similar lever arm of the next adjacent track device (Fig. 2), and its other arm 67 carrying at its end a roller 68 bearing against a down-turned flange 69 of the cam member 55. The bell crank is pivoted upon a trunnion 70 carried by the plate 62. The roller 68 is held normally in engagement with the flange 69 by means of a spring 71 extending between the arm 64 and the member 59 and serving, in addition to its function of maintaining the roller 68 in contact with the flange 69 as a means for normally retaining the cam member 55 in position to be actuated by the passage of a train (full line position, Fig. 3). In the case of the devices C_3 , the plate 62 and its trunnion 70 carry, in addition to the above mentioned bell crank lever 63, a bell crank lever 72 having an arm 73 connected with the cable or rod 42, hereinbefore described, and an arm 74 provided with a roller 75 in contact with the flange 69 of the cam member 55 and adapted for operation thereby to effect elevation of the spiked bar 26 through the medium of the mechanism hereinbefore described.

The arms 64 of the lever 63 in all of the devices C_1 , C_2 , C_3 upon the same side of the railroad track are interconnected by means of the cables or rods 4 and flexible connections or chains 66 in order that C_1 , C_2 and C_3 may successively impart motion to the fulcrum members 2 through cables or rods 4 and flexible connections or chains 77 connected with arms 64 of levers 63 of the devices C_3 as a train approaches, the flexible

connections 66 and 77 serving to permit flexing of the connections between the members C₁, C₂, C₃ and 2, respectively, when a successive operation of the members C₁, C₂, C₃ and D takes place.

Where the down-turned flange 69 of the cam member 55 extends around the end 58 and embraces the member 59, it is provided with a tongue 78 which enters the slot 61 to prevent raising of the end of the cam member, as hereinbefore indicated.

The devices D are similar in construction and operation to the devices C₃, except that these devices D being located across the roadway from the devices C₃ and the fulcrum members 2, the pull upon the fulcrum members must be reversed, and therefore the levers 79 and 80 controlled by the members D must act in the reverse direction, these levers serving respectively to return the signal members to initial "R. R. danger" position and to return the spiked bar 26 to depressed position, by means of the cables or rods 5 and the cables or rods 43 and their connections.

In order that the signal members located upon both approaches to the railway may be simultaneously operated by trains passing in either direction, I connect the two fulcrum members 2 by means of cables or rods 82 whereby actuation of one fulcrum member will actuate the other.

For the purpose of actuating the track adjacent devices C₁, C₂, C₃ and D, I prefer to use a device to be carried by the pilot of a locomotive, this device comprising in its preferred form (see Fig. 6) a roller 83 arranged for engagement with the track adjacent face of the downward-turned flanges 69 of the cam members and having a shoulder 84 adapted to ride upon the tops of the cam members, this roller being slidably mounted upon a spindle 85 in a bearing 86, pivoted at 87 to a bracket 88, suitably attached to the pilot 89. The roller is normally depressed by a spring 90. By this spring mounting of the roller, it will be seen that differences in relative position between the track adjacent devices and the roller caused by swaying of the locomotive may be compensated for.

Obviously, it is undesirable to have the roller 83 act upon the track adjacent devices when the locomotive is running backward, and to prevent such action of the roller, I provide it with a cam guide 91 adapted to strike against the ends 58 of the cam members and to impart movement to the bearing 86 upon pivot 87, whereby the roller will be tilted upon this pivot and ride over the ends of the cam members without actuating or damaging them.

If it is desired to prevent actuation of the track adjacent devices when the locomotive is running forward, the roller 83 may

be moved out of cam member engaging position by means of a rod or link 92 suitably connected with control means (not shown) in the cab of the locomotive by which movement may be imparted to the roller about its pivot 87 to raise the roller.

The operation of the device is substantially as follows:—Assuming that a train is approaching the crossing, it will, by means of the roller 83 mounted upon the locomotive pilot, first operate the track adjacent device C₁, which through its cable or rod 4 and the similar cables or rods of the devices C₂ and C₃ respectively, impart a quarter turn to the fulcrum member 2, which will in turn through its connections 1 with the signal devices A₁, A₂ and A₃ impart a quarter turn to the rotatable heads thereof to present to the view of the driver of a vehicle approaching upon the roadway, the plate bearing the legend "Train 400 feet". The train having passed the device C₁ will in turn approach and actuate the device C₂, which will, through its connections with the signal devices operate in the same manner as the device C₁ to move the rotatable heads of the signal devices through a second quarter turn to thereby present to the driver of the vehicle the plate bearing the legend "Train 300 feet". The train having passed the device C₂, will in turn approach and operate the device C₃ which will through its connections with the signal devices and the barrier turn the rotatable heads of the signal devices through a third quarter turn to thereby present to the driver of a vehicle the plate bearing the legend "200 feet stop", and will elevate the spiked bar 26 of the barrier. It will, of course, be understood that at the time of this last mentioned operation, the train is approximately 200 feet distant from the crossing, and the vehicle operator who thinks that he can take a chance of crossing the tracks ahead of the train in disregard of the warning will, upon reaching the railroad tracks present the tires of his vehicle to the projecting spikes of the barrier and will have them punctured or badly mutilated, depending upon whether he is running slowly or rapidly.

If the crossing is made ahead of the train, the driver will pay the penalty of having four practically useless tires, and will in addition carry with him unmistakable evidence that he has disregarded the warning duly given him that there was danger in attempting to make the crossing.

If he is struck by the approaching train, his tires if later recovered, will bear mute evidence of the fact that he disregarded the warning and took his life in his hands in attempting to make the crossing.

Obviously, this evidence would be of inestimable value in case of a civil action against the railroad, in showing negligence

on the part of the vehicle driver, and would tend to reduce the damages which he might recover from the railroad, or might even prevent any recovery of damages.

5 If a fine were imposed by statute, for crossing a railway in disregard of the warning given by the devices of my invention, and the driver who took a chance did succeed in crossing ahead of a train, the evidence borne by his tires of having come in contact with the barrier of my invention would almost certainly result in his detection and arrest.

After the train has operated the devices 15 C_1 , C_2 and C_3 , and has passed over the crossing, it will operate the device D which will, through its connections with the fulcrum members 2 and the signal devices A_1 , A_2 , A_3 and the barrier E, turn the rotatable heads 20 of the signal devices through the fourth quarter turn to thereby return them to initial position to present to vehicle drivers the plate bearing the legend "R. R. danger" and will actuate the mechanism hereinbefore 25 described, for returning the spiked bar 26 to depressed position, thus presenting to vehicles a clear crossing.

Although, in the interest of clearness of the drawings, the various rods and cables 30 are shown as unprotected by housings, these rods and cables may be suitably housed and lubricated to ensure their easy operation under all conditions. Furthermore, particularly where cables or other non-rigid connections are used, springs, of sufficient 35 strength to form non-expanding connections under ordinary operating conditions but capable of expansion to compensate for variations in the length of the connections, 40 may be installed between sections of such connections.

I have hereinbefore spoken of using either 45 electric or oil lamps for providing illumination of the signal devices. Obviously where electricity is available, as would generally be the case in urban and suburban crossings, 50 its use for the illumination of the signal devices would be practical and desirable, but in outlying districts, such as open country, 55 where electricity is not available, the use of oil lamps may be resorted to, although it would be perfectly feasible to use dry or storage batteries in connection with a suitable switch, as hereinbefore mentioned, for furnishing illumination for the signal devices.

It will thus be seen that I provide a safety device for railway crossings which not only gives ample warning to the drivers 60 of vehicles approaching the crossing upon the roadway, but in addition erects before them a barrier which no driver having regard for his property would cross, even though he might be inclined to take a chance 65 with his life. In addition, my invention is

well adapted for installation at grade crossings the approaches to which are "blind". Furthermore, it will be apparent that the signal devices, although I have shown and described them as located upon approaches 70 to a crossing running substantially at right angles to the railway, might be located upon approaches extending obliquely across the railway, and either comprising one road only crossing the railroad, or a number of 75 roads crossing same at the same point.

Although I have herein shown and described a particular embodiment of my invention, and have mentioned a number of changes which might be made therein, I do 80 not wish it to be understood that I thereby consider my invention as limited to this particular disclosure, but contemplate various changes in the construction, arrangement, and operation of the various parts comprising 85 the complete operative whole as within the spirit of the invention and the scope of the following claims.

What I claim is:

1. A safety device for grade crossings of 90 roadways with railways, including a signal device located upon the roadway, and a plurality of successively operable devices located adjacent to the railway tracks at suitable distances respectively from said crossing, 95 said track adjacent devices arranged for successive actuation by a train approaching the crossing for the purpose of operating said signal device to indicate the successive relative proximity of said train to said 100 crossing.

2. A safety device for grade crossings of 105 roadways with railways, including a plurality of signal devices located on the roadway at its approaches to the railway, and a plurality of successively operable devices located adjacent to the railway tracks at suitable distances respectively from the crossing, said track adjacent devices adapted for successive actuation upon the passage of a train 110 for operating said signal devices simultaneously.

3. A safety device for grade crossings of 115 roadways with railways, including a signal device located on the roadway and adapted to inform a driver on the roadway of successive points in the approach of a train to the crossing, and a plurality of devices located adjacent to the railway tracks at successive lessening distances from the crossing, 120 said track adjacent devices adapted to be operated successively upon the passage of a train to impart train position indicating operation to said signal device.

4. A safety device for grade crossings of 125 roadways with railways, including a plurality of visible signal devices located at varying distances from the railway respectively and adapted for operation to successively show positions in the approach of a 130

train to the crossing, a plurality of devices located adjacent to the railway tracks at successive lessening distances from the crossing and adapted to be actuated by a passing 6 train successively, and means connecting said track adjacent devices with said signal devices whereby upon successive independent operation of the track adjacent devices the signal devices will be simultaneously operated to indicate to a vehicle driver the successive lessening distance of the approaching 10 train from the crossing.

5. A safety device for grade crossings of roadways with railways, including a plurality of signal devices located upon the roadway, each of said signal devices being provided with a plurality of visible signals adapted for successive presentation to the view of an approaching vehicle driver and 15 all of the signal devices connected for simultaneous operation to present the same visible signal whereby the driver is advised of a plurality of stages in the approach of a train to the crossing, and means actuated 20 successively by an approaching train and operatively connected with said signal devices whereby said visible signals will be appropriately successively presented to view.

6. A safety device for grade crossings of 25 roadways with railways, including a plurality of signal devices upon the roadway, each of said signal devices having a rotatable head bearing a plurality of appropriate train position indicating visible signals 30 adapted for successive separate presentation to the view of an approaching driver to apprise him of the relative proximity of a train to the crossing, and a plurality of track adjacent devices operable successively upon 35 the passage of a train for independently 40 successively imparting rotation to the rotatable heads of said signal devices simultaneously, whereby the same visible signal is simultaneously displayed by all of the signal 45 devices.

7. A safety device for grade crossings of 50 roadways with railways, including a plurality of simultaneously operable signal devices upon the roadway, track adjacent devices 55 operable upon the passage of a train and arranged at successive lessening distances from the crossing, and means including levers forming a part of said track adjacent devices and operating coincidently therewith and connections between said levers and said signal devices, whereby when 60 said levers are successively actuated by a passing train their motion will be transmitted to said signal devices to impart thereto successive simultaneous operation.

8. A safety device for grade crossings of 65 roadways with railways, including a plurality of simultaneously operable roadway signal devices, a plurality of track adjacent

devices located at successive lessening distances from the roadway on one side thereof, means providing connections between said track adjacent devices and signal devices for actuating said signal devices to indicate successive distances of a train from 70 the crossing corresponding to the relative location of the several track adjacent devices with respect to the crossing, and a track adjacent device on the other side of the roadway and operable after the passage 75 of a train over the roadway, said last mentioned track adjacent device being suitably connected with said signal devices to so operate same as to thereby indicate that the 80 crossing is clear.

9. A safety device for grade crossings of roadways with railways, including a signal device on the roadway provided with means for visibly indicating successive positions of a train during its approach to the crossing, a plurality of track adjacent devices arranged at successive lessening distances from the crossing and train actuated successively, connections between said track adjacent devices and said signal device for 85 actuating said signal device in response to the actuation of said track adjacent devices, and a barrier arranged transversely of the roadway adjacent to the railway and actuated in response to the actuation of the 90 track adjacent device nearest to the roadway, whereby upon actuation of said last mentioned track adjacent device said signal device and barrier will be simultaneously operated to apprise a vehicle driver 95 of the proximity of a train to the crossing and to obstruct the passage of the vehicle respectively.

10. A safety device for grade crossings of roadways with railways, including a signal 100 device on the roadway, provided with means for visibly indicating successive positions of a train during its approach to the crossing, a plurality of track adjacent devices arranged at successive lessening distances 105 from the crossing and train actuated successively, connections between said track adjacent devices and said signal device for actuating said signal device in response to the actuation of said track adjacent devices, a barrier arranged transversely of the roadway adjacent to the railway and actuated in response to the actuation of the track 110 adjacent device nearest to the roadway, whereby upon actuation of said last mentioned track adjacent device said signal device and barrier will be simultaneously operated to apprise a vehicle driver of the proximity of a train to the crossing and to 115 obstruct the passage of the vehicle respectively, and train actuated means operable after a train has passed the crossing for simultaneously operating said signal device 120

125

and barrier to indicate a clear crossing and remove the obstruction of the barrier respectively.

11. A safety device for grade crossings of roadways with railways, including a signal device on the roadway provided with means for visibly indicating successive positions of a train during its approach to the crossing, a plurality of track adjacent devices arranged at successive lessening distances from the crossing and train actuated successively, connections between said track adjacent devices and said signal device for actuating said signal device in response to the actuation of said track adjacent devices, and a barrier including a plurality of projectable spikes arranged transversely of the roadway adjacent to the railway and actuated in response to the actuation of the track adjacent device nearest to the roadway, whereby upon actuation of said last mentioned track adjacent device said signal device and barrier will be simultaneously operated to apprise a vehicle driver of the proximity of a train to the crossing and to project said spikes to obstruct the passage of the vehicle respectively.

12. A safety device for grade crossings of roadways with railways, including a barrier arranged transversely of the roadway adjacent to the railway and having a casing, a plurality of projectable spikes arranged in said casing and normally enclosed thereby, means in said casing for projecting said spikes above the plane of the surface of the roadway, and train actuated means connected with said spike projecting means for imparting spike projecting movement thereto upon the approach of a train to the crossing.

13. A safety device for grade crossings of roadways with railways, including a barrier arranged transversely of the roadway adjacent to the railway and having a casing, a plurality of projectable spikes arranged in said casing and normally enclosed thereby, means in said casing for projecting said spikes above the plane of the surface of the roadway, train actuated means connected with said spike projecting means for imparting spike projecting movement thereto upon the approach of a train to the crossing, and train actuated means connected with the spike projecting means and serving to return said spikes to normal position within the casing after the train has passed the crossing.

14. A safety device for grade crossings of roadways with railways, including a barrier arranged in the roadway adjacent to the railway and comprising a plurality of projectable spikes, means for elevating said spikes above the plane of the surface of the roadway, and train actuated means con-

nected with the spike elevating means and adapted upon approach of a train to the crossing to elevate said spikes and upon passage of the train over the crossing to return said spikes to normal depressed position.

15. A safety device for grade crossings of roadways with railways, including a barrier located in the roadway adjacent to the railway and having a spiked bar adapted for elevation to project the spikes above the plane of the surface of the roadway, a lever member cooperating with said bar and adapted upon actuation to elevate same, and train actuated means operatively connected with said lever member, whereby upon approach of a train to said crossing said bar will be elevated and said spikes projected and upon passage of said train over the crossing said bar will be lowered and the spikes returned to normal depressed position.

16. A safety device for grade crossings of roadways with railways, including a barrier arranged in the roadway adjacent to the railway and comprising a casing, a spiked bar arranged for vertical sliding movement within said casing, a plurality of lever members cooperating with said bar and adapted upon actuation to raise the same to thereby project said spikes above the plane of the surface of the roadway, a cover for said casing provided with openings through which said spikes are projected when the bar is raised, a movable plate normally covering said openings, connections between said bar and plate whereby when said bar is raised said plate will be moved to uncover said openings to permit the passage of the spikes therethrough and when said bar is lowered said plate will be returned to normal opening covering position, and train actuated means operatively connected with said lever members and adapted upon approach of a train to the crossing to raise said bar and project said spikes and upon passage of the train over the crossing to cause said bar to return to normal depressed position.

17. A safety device for grade crossings of roadways with railways, including a barrier located in the roadway adjacent to the railway and comprising a casing, a guide frame carried within said casing, a spiked bar mounted for vertical sliding movement within said frame, a plurality of lever members pivotally mounted in said frame and serving upon actuation to raise said bar and project said spikes above the plane of the surface of the roadway, lever plates mounted exteriorly of said frame and within said casing and rigidly connected with said lever members through arcuate slots provided in said frame, links connected with said lever

plates for moving them simultaneously upon their pivots, and train actuated devices operatively connected with said links, whereby when a train approaches the crossing said 5 spikes will be projected and when the train passes over the crossing the spikes will be returned to normal depressed position.

18. A safety device for grade crossings of roadways with railways, including a barrier arranged in the roadway adjacent to the railway and comprising a casing, a guide frame mounted within said casing, a spiked bar vertically slidable within said frame, means carried by said frame for 15 raising said bar, the bar being of sufficient weight to lower automatically when released, a cover for said casing provided with openings for the passage of the spikes when said bar is raised, a movable plate for normally closing said openings when said bar 20 is in normal depressed position, cam members pivoted to said frame and to which

said plate is connected, cooperating means on said bar and cam members whereby movement of the bar will move said cam 25 members and the plate carried thereby, and train actuated means operatively connected with the bar raising means, whereby when a train approaches the crossing said bar will be raised and the plate moved out of opening covering position to permit projection of the spikes therethrough, and when the train has passed the crossing the bar raising means will be depressed, the bar will return to lowered position and the plate will 30 be thereby returned to normal opening covering position.

In testimony whereof I have hereunto set my hand this 16th day of January, A. D. 1924.

IRA D. WALTER.
